(57) **CLAIM**

The ornamental design for an washing machine, as shown and described.

DESCRIPTION

FIG. 1 is a perspective view of the washing machine in accordance with the present invention;

FIG. 2 is a front elevation view thereof, it being understood that the rear elevation view is a mirror image thereof;

FIG. 3 is a left-side elevation view thereof;

FIG. 4 is a right-side elevation view thereof;

FIG. 5 is a top view thereof;

FIG. 6 is a bottom view thereof;

FIG. 7 is a partially exploded view thereof, illustrating the washing basket separated from the washing basin;

FIG. 8 is a perspective view of the washing basin of the washing machine in accordance with the present invention;

FIG. 9 is a front elevation view thereof, it being understood that the rear elevation view is a mirror image thereof;

FIG. 10 is a left-side elevation view thereof;

FIG. 11 is a right-side elevation view thereof;

FIG. 12 is a top view thereof;

FIG. 13 is a bottom view thereof;

FIG. 14 is a perspective view of the washing basket in accordance with the present invention;

FIG. 15 is a front elevation view thereof, it being understood that the rear elevation view is a mirror image thereof;

FIG. 16 is a left-side elevation view thereof, it being understood that the right-side elevation view is a mirror image thereof;

FIG. 17 is a top view thereof; and,

FIG. 18 is a bottom view thereof.

The elements depicted in broken line in the various figures are included for environmental purposes only, and form no part of the claimed design.

1 Claim, 18 Drawing Sheets
